UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 13,377, dated October 31, 1882.

Application filed August 11, 1882. Term of patent 3½ years.

To all whom it may concern:

Be it known that I, WINTHROP L. JACOBS, of East Orange, in the State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The design consists of an irregular net-work of large and small conventional figures disposed upon a plain ground. The large figures are variously shaped, as shown, and are con-

nected together by short angular right-lined stems in kaleidoscopic groups. The space between these larger figures is filled in with smaller figures of various geometric and conventional forms and shapes, carried on the short connecting-stems. The design is fully and clearly shown in the accompanying photograph.

I claim—

The design for carpets, consisting of the design substantially as herein shown and described.

WINTHROP L. JACOBS.
